UNITED STATES PATENT OFFICE.

JOSEPH N. VASEY, OF BROOKFIELD, ILLINOIS.

DESIGN FOR A PHONOGRAPH-CABINET.

53,754.

Specification for Design.

Patented Aug. 26, 1919.

Application filed February 20, 1919. Serial No. 278,309. Term of patent 3½ years.

To all whom it may concern:

Be it known that I, JOSEPH N. VASEY, a citizen of the United States, residing at Brookfield, in the county of Cook and State of Illinois, have invented a new, original, and ornamental Design for Phonograph-Cabinets, of which the following is a specification, reference being had to the accompanying drawing, forming a part thereof.

The figure is a perspective view of the

interior of a phonograph cabinet showing my new design.

I claim:

The ornamental design for a phonograph cabinet as shown.

In witness whereof I hereunto subscribe my name this 14th day of February, A. D. 1919.

JOSEPH N. VASEY.
